CAPSULE CLEANER

Norman L. Kisling, Baltimore, Md.

Application January 24, 1945, Serial No. 574,284

3 Claims. (Cl. 51—163)

This invention relates to new and useful improvements in capsule cleaners.

Capsules after being filled always have some of the drug or chemical adhering to the outside of the filled capsule.

An object of this invention, therefore, is to clean filled capsules after pharmacists have filled them for prescriptions.

Another object of this invention is to clean the capsule so that no trace or taste of the drug remains on the outside of the capsule for the patient to taste when taking the capsule.

A further object of the invention is to provide a device that cleans and deposits a tasteless, clean, sanitary capsule in a container without being touched by the hands of the pharmacist after the capsules have been placed therein.

With the above and other objects in view, the invention consists of certain novel details of construction and combination of parts hereinafter more fully described and claimed, it being understood that various modifications may be resorted to within the scope of the appended claims without departing from the spirit or sacrificing any of the advantages of the invention.

The invention will be readily understood by reference to the accompanying drawing forming a part of this specification in which:

Fig. 1 is a front view of an embodiment of the invention.

Fig. 2 is a sectional view taken on the line 2—2 of Fig. 1.

Fig. 3 is a sectional view taken on the line 3—3 of Fig. 2, and

Fig. 4 is a top plan view of the draw of the device.

Referring more in detail to the drawing wherein like numerals designate like parts throughout, the numeral 10 refers to the body of the cleaner which is preferably rectangular in form and may be made of wood, glass, metal or plastic.

The body comprises vertical sides 11 and vertical ends 12 having a bottom 13 attached thereto. At approximately one-third of the distance from the open top of the body to the bottom 13 there is positioned a horizontal partition 14 which forms the bottom of an open container for receiving empty capsules prior to the filling thereof.

The sides 11 have shoulders 15 formed therein at an approximate distance of one-third of the remaining space between the partition 14 and bottom 13 which are adapted to slideably receive and support a draw 16 comprising vertical sides 17, vertical ends 18, and a perforated bottom 19.

The front end of the draw is provided with a

knob 20 for removing the draw from the body 10.

The front end of the draw 16 is adapted to be received in a recess 21 formed in the front end of the body in order that the front end of the draw can close flush with the front end of the body.

The sides 17 of the draw 16 are provided with square openings 22 which are used to disperse the capsules into a container intended to be given to the customer.

The perforated bottom 19 of the draw 16 forms the top of a closed container in which is placed dry white sand or granulated sugar.

When the cleaner is to be used the filled capsules are dropped into the draw and the cleaner is turned upside down and the sand or sugar is permitted to filter through the perforated bottom of the draw onto the capsules. After being shaken several times, the position of the draw is reversed to permit the sand and sugar to filter back into the bottom container.

The cleaner is shaken again to be sure all the sugar and sand has left the draw which is then removed.

25 The filled clean capsules are then discharged through the openings in the side of the draw into a container.

From the above description and operation of the device, it will be seen that there has been provided a cleaner which embodies the advantageous features described and which may be modified in various particulars without departing from the spirit of the invention or the scope of the appended claims.

35 Having thus described the invention, what is claimed as new and desired to be secured by Letters Patent is:

1. A device of the character described for cleaning capsules comprising a body, a partition in 40 said body, a draw for holding said capsules slideably mounted in shoulders formed in the sides of said body, said draw having a perforated bottom and a container in the bottom of said body adapted to receive an abrasive material for cleaning said capsules when said body is inverted to permit said material to enter said draw.

2. The invention as described in claim 1 wherein openings are provided in the side of said draw.

3. The invention as described in claim 1 wherein said draw closes flush with the front of said body and means is provided on the front of said draw for removing said draw from said body.
